CLAIM

The design for a toy orrery/planetarium, as shown and described.

DESCRIPTION

FIG. 1 is a front, left side perspective view of a toy orrery/planetarium showing my new design, the broken line showing of the spheres and supports are for illustrative purposes only and form no part of the claimed design;

FIG. 2 is a top plan view thereof;

FIG. 3 is a front elevation view thereof;

FIG. 4 is a right side elevation view thereof;

FIG. 5 is a left side elevation view thereof; and,

FIG. 6 is a rear elevation view thereof.

The bottom is plain and unornamented.

1 Claim, 4 Drawing Sheets
